[57] CLAIM

The ornamental design for a liquid product dispenser cabinet, as shown and described.

DESCRIPTION

FIG. 1 is a top, front, and left side perspective view of a liquid product dispenser cabinet showing my new design; FIG. 2 is a front elevational view thereof, the broken-line disclosure of portions of liquid concentrate bottles within the cabinet being for illustrative purposes only and forming no part of the claimed design;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
